SHOE

John Edward Disch, Dolgeville, N. Y., assignor
to Daniel Green Company, Dolgeville, N. Y., a
corporation of Massachusetts

Application March 3, 1933, Serial No. 659,469

4 Claims. (Cl. 36—2.5)

My invention relates to footwear more particularly to women's shoes or slippers and especially to that type of slipper commonly known as mules, in which a back strap is used for engagement with the upper portion of the heel to hold such shoe or slipper on the foot.

Heretofore such back straps have been attached to the shoe or slipper in such a way as to create wrinkles in the strap when in use 10 with the pull back at an angle that does not give the proper elasticity or the correct direction in fitting the strap to the heel.

The objects of my invention are, among other things, to provide a new and improved back strap construction for such shoes or slippers in which the back pull on the strap to put on and adjust the shoe to the foot is not only in the proper direction, but also will not disclose the elastic goring which is used to fasten the forward ends 20 of the strap to the shoe. Furthermore my improved back strap enables the same to stand up without wrinkles, and also secures a much closer fit about the upper portion of the heel by reason of the fact that a pull on the strap may be exerted lengthwise or backwardly as well as in 25 an up and down direction, thereby enabling such back strap to make a close fit around the heel.

Such compound movement for this back strap not only draws the foot into the toe of the shoe 30 or slipper, but also holds the heel of the foot snugly to the surface of the slipper heel, and at all times the elastic goring is effectively concealed under the sock lining of the shoe.

Other objects and advantages will appear from 35 the following description when taken with the annexed drawing in which—

Fig. 1 is a perspective view of a shoe or slipper embodying my improved back strap construction;

Fig. 2 is a top plan view with parts of the sock lining and canvas pieces removed to open up the shoe to show how the back strap is fastened to the sole;

Fig. 3 is a section on the line 3—3 of Fig. 2;

Fig. 4 is a bottom plan view on the line 4—4 of Fig. 3;

Fig. 5 is a detail view showing the position of the elastic goring when the strap is pulled back for adjustment around the heel; and

Fig. 6 is a detail view showing the position of the goring for the up and down pull in such strap.

Similar numerals refer to similar parts throughout the several figures.

Referring to the drawing the upper 7 of the

shoe or slipper is fastened in the usual way to the outer sole 8 to which is affixed the heel 9 (Fig. 1). The inner sole 10 (Fig. 3) holds the marginal edges of the upper 7 to the sole 8. Fastened to the shank of the sock lining 24 of the shoe or slipper by any suitable means, such as adhesive, are two mutually parallel pieces of canvas or other fabric 11 and 12 that are united along their inner edges by cross-stitching 13, which also holds the inner ends of the goring strips 18, 19, 20 and 21 that are arranged between the canvas pieces 11 and 12 and the inner sole 10.

In fabricating the shoe the goring strips, which have been attached to each other and to the inner edges of the canvas pieces 11 and 12 as shown in Fig. 4, are glued or fastened at their inner ends to the insole 10, the ends of the canvas pieces beyond the goring strips are also glued or fastened to the insole 10, and the sock lining 24 is glued or otherwise secured to the upper surfaces of the canvas pieces 11 and 12 and insole 10. The sock lining 24 and canvas pieces 11 and 12 with the attached goring strips 18, 19, 20 and 21 comprise an integral part of 25 the shoe attached to the inner sole 10. Such glued single unit when attached to the insole as above described, not only protects the goring strips 18—21 from the glue applied to the sock lining 24, but also provides a construction in 30 which the parts forming the shank of the shoe are bonded together as an integral whole that prevents buckling of the sock-lining relative to the insole at the shank of the shoe as the latter is flexed when worn in walking. Furthermore 35 the canvas pieces 11 and 12 provide a smooth surface for the goring strips 18—21 to slide on when pulled from their normal position; such canvas pieces 11 and 12 also cover any roughness on the under surfaces of the sock lining 24 and furthermore protect the edges of the sock lining cover which otherwise would become loosened and distorted by the complementary sliding and pulling of the goring strip ends as the 40 slipper is worn in use.

Or the sock lining 24, canvas pieces 11 and 12, goring strips 18, 19, 20 and 21 and strap 14 may be first assembled as a unit. This is done by first stitching the inner ends of the goring pieces and the inner edges of the canvas pieces together and to each other by stitching 13, the strap 14 having been earlier stitched to the goring pieces 18—21. The upper surfaces of the canvas pieces 11 and 12 are then adhesively or otherwise connected to the under surface of 50 55

the sock lining 24 at its shank. This unit then has an adhesive applied to the under surfaces of the canvas pieces 11 and 12 on that part of their ends which project beyond the goring pieces 5 18—21, to the stitching 13 and to the forward and rear portions of the under surface of the sock lining 24 and the unit is then superimposed upon an insole 10. The setting of the adhesive attaches the unit to the insole 10.

10 The back strap 14 is preferably formed of light leather lined with fabric material, and is cut in more or less U-shape (Figs. 1 and 2) with the tab 15 at the top of the rear end of the strap 14 to enable the wearer readily to grasp the strap 14 15 when putting on the slipper. The forward ends 16 and 17 of the back strap 14 each have two strips of elastic goring 18 and 19 (secured to the end 16), and similar pieces of goring 20 and 21 (secured to the end 17) by lines of stitching 22 and 23 respectively.

20 These strips of goring 18, 19, 20 and 21 are cut on the bias and the adjacent pieces 18, 19 and 20, 21 preferably overlap each other as shown in Figs. 2 and 4 with the forward strips 18 and 20 sliding over the back strips 19 and 21. To maintain this overlapping relationship (Fig. 4), the forward ends of the goring strips 18, 19, 20 and 21 are passed beneath the canvas pieces 11 and 12 and are united thereto by the cross-stitching 13 which 25 may be reinforced by glue or other adhesive when the canvas is secured to the inner sole 10.

25 Since the goring strips 18, 19, 20 and 21 have been secured to the under surfaces of the canvas pieces 11 and 12 as hereinbefore described, those 30 portions of the under surfaces of the canvas pieces 11 and 12 that project beyond the goring strips are glued or otherwise secured to the inner sole 10 along the shank of the slipper. The sock lining 24 superimposed over the goring strips 18, 19, 20 and 21, and having been glued or otherwise secured to the canvas pieces 11 and 12, covers these goring strips and the pieces 11 and 12 prevent the glue from contacting with the goring strips 18—21, as shown in Figs. 2 and 3. 35 Such sock lining 24 fully conceals the canvas pieces 11 and 12 as well as the goring strips 18, 19, 20 and 21 even when the back strap 14 is pulled back as shown in Fig. 5.

40 In use, the back strap 14 is grasped by the tab 15 and pulled back without wrinkling as shown in Fig. 5, the goring strips 18, 19, 20 and 21 sliding over one another as shown in Fig. 5; while Fig. 6 illustrates how an up and down movement 45 may be imparted to the strap 14.

45 According to my improved back strap construction the two forward strips of goring 18 and 20 slide slightly over the two back strips 19 and 21 (Fig. 5). When the strap 15 is fully pulled back, the wearer can readily give an up and down movement in which the two back strips 19 and 21 allow this up and down pull (Fig. 6), while the forward strips 18 and 20 stretch in unison with the back strips 19 and 21 (Fig. 5) in permitting the backward and forward pull. Hence the cutting of 50 these goring strips 18, 19, 20 and 21 on the bias, as well as the stitching of same in overlapping relationship so that the forward strips 18 and 20 slide over the two back strips 19 and 21, secure a compound movement (forward and backward

as well as up and down) for the heel strap 14 without wrinkling the latter, and also without exposing the goring strips which in all positions are concealed by the sock lining 24 that is also prevented from lifting because of the canvas pieces 11 and 12 securely fastened to the inner sole 10.

5

From the foregoing description it will be clear that my improved back strap is such as to permit the shoe or slipper to be readily put on, or removed from, the foot without wrinkling the strap, and that in use such back strap fits snugly about the heel through the conjoint movements of the elastic goring strips in overlapped positions beneath the sock lining 24, and that this two-way motion for the strap precludes any wrinkling 10 thereof when the strap is pulled back.

I claim as my invention:—

1. A shoe or slipper having a back strap to encircle the upper heel of the wearer with each forward end of the strap carrying a pair of overlapping mutually parallel elastic goring strips oppositely disposed and having their inner ends only secured to the sole of the shoe.

20

2. A shoe or slipper having a back strap to encircle the upper heel of the wearer with each forward end of the strap carrying a pair of partially overlapping mutually parallel elastic goring strips, each pair being oppositely disposed and having their inner ends only secured to the sole of the shoe to allow a complementary sliding movement for the strip of each pair independently of the other, whereby the strap has a compound movement in two directions without wrinkling.

25

3. A shoe or slipper having a back strap to encircle the upper heel of the wearer with each forward end of the strap carrying a pair of partially overlapping mutually parallel elastic goring strips, the forward ends of which are fastened in oppositely disposed relationship along the center line 30 of a pair of mutually parallel fabric pieces, the ends of which beyond the goring strips are secured to the sole, said strips of each pair having their inner ends attached to the insole and having complementary sliding two-way movement beneath 35 said fabric pieces independently of each other, whereby the strap has a compound movement in two directions without wrinkling.

40

4. A shoe or slipper having a back strap to encircle the upper heel of the wearer with each forward end of the strap carrying a pair of partially overlapping mutually parallel elastic goring strips, the forward ends of which are fastened in oppositely disposed relationship along the center line of a pair of mutually parallel fabric pieces, the ends of which beyond the goring strips are secured to the sole, said strips of each pair having their inner ends attached to the insole and having complementary sliding two-way movement beneath 45 said fabric pieces independently of each other, whereby the strap has a compound movement in two directions without wrinkling, and a sock lining superposed over the sole and fastened to said fabric pieces over said elastic strips to conceal the latter when the strap is 50 pulled without interfering with the said complementary sliding movement of said strips.
